UNITED STATES PATENT OFFICE.

JOHN STEPHENSON, OF NEW YORK, N. Y.

CAR-BODY TRUSS.

SPECIFICATION forming part of Letters Patent No. 319,525, dated June 9, 1885.

Application filed December 8, 1884. (No model.)

To all whom it may concern:

Be it known that I, JOHN STEPHENSON, a citizen of the United States, and a resident of the city, county, and State of New York, have 5 invented an Improved Truss for Tram-Cars, of which the following is a specification.

My invention is one of a class for supporting the body of a tram-car in its constructed shape, and is especially applicable to those 10 known as "summer-cars." For this purpose I make a truss independent of the car-body and place it under the car-sills. The upper chord of the truss conforms in line to the under side of the car-sill to which it becomes attached, and the under chord unites with the 15 upper chord at their ends, from whence it deflects until the pedestals are reached, and thence between the pedestals the chords are parallel. The pedestals act as queen-posts 20 between the chords.

In the drawings, Figure 1 is a side view of part of a tram-car, in part section, illustrating my improvement. Fig. 2 is an enlarged view of a pedestal, in part section, showing the attachments. Fig. 3 is an inverted view of the 25 pedestal.

The following elements on both sides of the car constitute the complete truss: Upper chord, two central eye-rods; four pedestal 30 bed-plates; four end eye-rods; four strut-thimbles with fastening-bolts. Lower chord, two central stay-bars; four pedestal-bottoms; four base-bars; four strut-braces, which abut on the union-bars of the pedestal-bottoms; four strut-thimbles with fastenings, which also form 35 parts of the upper chord.

The upper chord of the truss is constructed by placing beneath the sills A four pedestals, B, separated at proper distances for the wheel-base of the car. The inner ends of the pedestal bed-plates are coupled by central eye-rods, L', with their ends secured preferably to the 40 pedestal fastening-bolts t'. Similar bolts, t, at the farther end of the pedestal bed-plates receive the ends of four eye-rods, L, whose farther ends are lodged on the fastening-bolts t' in the nearer ends of the strut-thimbles D.

The lower chord: From each strut-thimble 45 D descends a strut-brace, E, with its foot beveled to fit the face of the pedestal union-bar n, connecting the front and rear parts of the pedestal, and the two pedestals at one side of the

car are coupled by a stay-bar, F, with its ends beveled to fit the inner union-bars, the ends of the strut-braces and stay-bars being secured 55 to the union-bars by angle-bolts u, as shown. Crossing the jaws of each pedestal is a base-bar, H, with each of its upper faces bearing against the lower faces of the union-bars of the pedestal, and its ends abutting against the 60 ends of the strut-brace and stay-bar, and secured to the union-bars by bolts w. The parts thus described when united form the under chord of the truss.

The upper and lower chords unite at their 65 ends with the strut-thimbles D, and are separated toward their middles by the pedestals, acting as queen-posts, supporting the two chords, and giving to the truss its proper form and consistency.

The pedestals are made of such form and strength that for ordinary service they are capable of sustaining the sections of the lower chord of the truss without the brace-bars H, which are introduced for possible requirements, and are capable of removal without 75 disorganizing the truss.

The base-bar answers the double purpose of a key to the arch of the lower chord of the truss, and also the bridle or retainer keeping 80 the axle-box within the pedestal-jaws. The connection of the strut-thimbles by eye-rods and bed-plates prevents the strut-braces from thrusting outward the thimbles and letting down the truss.

The eye-rods connecting the pedestal bed-plates and those connecting the pedestals with the thimbles are shown as placed on the usual fastening-bolts of those parts, thereby simplifying construction. They may, however, be 90 connected in any suitable manner.

I do not here claim, broadly, a truss combined with the sill of a car, as this is the subject of an application filed by me July 16, 1884, Serial No. 137,903.

I claim—

1. A tram-car with body supporting truss, having its upper chord at either side of the car, consisting of the following elements in combination, viz: one central eye-rod, two pedestal bed-plates, two end eye-rods, two strut-thimbles, and fastening-bolts, substantially as described.

2. A tram-car with body-supporting truss,

having its lower chord at each side of the car, consisting of the following elements in combination, viz: one center stay-bar, two pedestals, two pedestal base-bars, without fastening 5 connection with either stay-bar or strut-brace, two strut-braces, two strut-thimbles, and fastening-bolts, substantially as described.

3. A tram-car with the body supported by a truss made of the following elements, viz: 10 two central eye-rods uniting four pedestals with four end eye-rods connecting with four strut-thimbles holding the upper ends of four struts, with their feet fastened to four pedestals, united in couples by two stay-bars fast to 15 the union-bars of pedestals, and carrying four base-bars crossing the pedestals' jaws, and fastening-bolts, substantially as described.

4. A tram-car with supporting-truss under each sill, the pedestals forming queen-posts of

the truss, and the bed-plates of the pedestals 20 constituting sections of the upper chord of the truss, substantially as described.

5. A tram-car with truss under its sills, a section of each lower chord crossing the open jaws of a pedestal, and removable without 25 disorganizing the truss, substantially as described.

6. A tram-car-body truss with the upper chord connecting the pedestals and strut-thimbles by eye-rods secured on the fastening-bolts 30 of pedestals and thimbles.

In testimony whereof I have signed my name to this specification in the presence of two subscribing witnesses.

JOHN STEPHENSON.
